FIRE EXTINGUISHER DISCHARGE DEVICE

Harry Ensminger, Milburn, N. J., assignor to
C-O-Two Fire Equipment Company, Newark,
N. J., a corporation of Delaware

Application October 20, 1950, Serial No. 191,109

8 Claims. (Cl. 169—11)

1

This invention relates to an apparatus for extinguishing fires, and particularly to a discharge device for carbon dioxide used as an extinguishing medium.

It is important, in most cases, for the effective extinguishment of fire by carbon dioxide, that the discharge device or nozzle be such that as large a proportion as possible of the issuing fluid be converted into carbon dioxide snow. The carrying quality of a stream is improved with an increase in snow content as well as its effectiveness in extinguishing a fire. Further, in order to facilitate its maneuverability, the discharge nozzle should be as compact as possible.

Prior devices have been provided for use in discharging carbon dioxide as a fire extinguishing medium, such as the device shown and described in United States Patent No. 1,993,696 issued on March 5, 1935, to S. E. Allen et al., and that shown and described in a co-pending application of Joseph E. Kucher, filed June 7, 1947, Serial No. 753,297, now U. S. Patent No. 2,547,018.

The present invention is an improvement over the Kucher device in that the present invention provides a compact discharge device that is particularly suitable for use in discharging a large quantity of low temperature carbon dioxide at a faster rate than is possible with the prior devices of similar size.

Another object of the invention is to provide an improved device for discharging carbon dioxide in which the stream of carbon dioxide issuing from the orifice or jet is expanded in a region of extremely low temperature so that the expanding fluid is prevented from absorbing heat during the initial period of its expansion.

Another object of the invention is to provide an improved device for discharging carbon dioxide at a high rate of discharge and which is compact in construction and light in weight.

Another object of the invention is to provide an improved discharge device for carbon dioxide that is simple and economical in manufacture, efficient in operation and durable in use.

In accordance with the invention, the foregoing objects are accomplished by providing a device for discharging liquefied carbon dioxide in which the fluid is expanded and deflected back over itself under a certain amount of back pressure so that the initially expanding fluid is surrounded by further expanded fluid of extremely low temperature, the expanding fluid being redirected so as to prevent the formation of eddy currents and insure a smooth evenly distributed flow.

2

This construction is advantageous in that the initially expanding fluid is prevented from absorbing heat from the atmosphere or from adjacent portions of the discharge device. Due to the absence of heat, the temperature of the expanding fluid immediately drops to a value at which snow is readily formed in a large proportion to the amount of fluid discharged. A secondary result is that the turbulence caused by the reversed flow produces larger particles of snow which provide better carrying properties in the discharged stream. The larger particles of snow also evaporate into gas at a proportionally slower rate and are thus more effective as a fire extinguishing agent. Another advantage is that by the practical elimination of eddy currents in the discharge stream, a flow of better carrying characteristic is obtained.

Other objects and advantages of the invention will be apparent from the following description and from the accompanying drawing, which shows, by way of example, an embodiment of the invention.

In the drawings:

25 Figure 1 is a perspective view of a hose reel carbon dioxide installation including a discharge device in accordance with the invention.

Figure 2 is a vertical sectional view of the discharge device.

30 Figure 3 is an end view of the discharge device.

Referring to the drawing there is shown in Figure 1 a discharge nozzle in accordance with the invention shown as attached to the discharge end of a hose 2 wound on a wall or truck mounted hose reel 4. The hose reel 4 may be connected by supply pipe 5 to a source (not shown) of fire extinguishing fluid, such as carbon dioxide. A main valve 6 is connected in the supply pipe 5 to shut off the fire extinguishing fluid supply to the hose reel 4. Another valve 7 is inserted in the hose line 2 adjacent the discharge nozzle 1 so as to provide means for the intermittent discharge of the fire extinguishing fluid. While the discharge device or nozzle is shown as attached to a hose reel, it is to be understood that it might be alternatively connected to a built-in system or to a truck mounted supply container.

The discharge device or nozzle shown in section in Figure 2 includes a housing or a body member 8 adapted to be connected to a semi-flexible operating handle 9 or extension of the hose 2. The body member 8 has a passage 10 extending therethrough providing an inlet and outlet for the fire extinguishing fluid. The operating handle 9 may be connected in threaded engage-

ment with the housing 8, or any other suitable connecting construction may be used. In the discharge side of the body member 8 is an orifice member 11 having a longitudinal discharge orifice 12 and a plurality of transversely extending orifices 14 in its side wall.

The orifice member 11 is preferably secured in the outlet passage 10 by threaded engagement with the wall thereof; or any other suitable connecting construction might be used, such as a friction fit. The orifices 14 are preferably equally spaced about the periphery of the wall of the orifice member 11 and are positioned on the side wall a short distance from the end of the body member 8. The relative proportions of the total area of the orifices 14 and that of the axial orifice 12 is such that approximately sixty to seventy per cent of the fluid is discharged through the orifices 14, the remaining thirty to forty per cent being discharged through the orifice 12.

An outer shield or redirecting member 15 preferably of generally cylindrical shape is secured to the body member 8 and is positioned with its open end directed outwardly. The shield 15 may be made of metal or of plastic material as desired. In order to receive the discharge end of the body member 8, an opening 16 is made in the end wall of the redirecting member 15. To strengthen the construction a stiffening disc 17 with an apertured center is placed about the opening 16 of the shield 15 and made with aligned apertures extending into a flange 18 of the body member 8 to receive screws 19 to secure the shield 15 in position to the body member 8.

In order that the issuing fluid is deflected back over itself and expanded in a heat exchange relationship, a plurality of baffle members are secured in position spaced from the orifice. An inner generally cone-shaped baffle member 20 with a flattened end 21 is apertured as indicated at 22 and secured in position with an apertured flange 24 adapted to receive bolts 25 extending through a spacing member 26. Positioned outwardly from the baffle member 20 is a second baffle member 29 of similar construction, likewise having a flattened end 30 with an aperture 31, the baffle member 29 secured in position with an apertured flange 32 to receive the bolts 25, and separated from the baffle member 20 by a spacing member 34. Outwardly from the baffle member 29 is a third baffle member 35 made in a generally similar shape with a flattened end 36 having an apertured flange 37 to receive the bolts 25 and separated from the baffle member 29 by a spacing member 39. The baffle member 35 differs from the baffle member 29 and 29 in that it does not have an apertured end wall. The baffle members 20, 29 and 35 are preferably made with their outer diameters progressively reduced. That is, so that the diameter of baffle member 29 is less than that of baffle member 20, and, the diameter of the member 35 is less than that of baffle member 29 to thereby provide a space of increasing annular section for the expanding fluid as it issues from the redirecting member 15. The assembly of baffle and spacing members is secured together by nuts 40 attached to the ends of the bolts 25. It is to be understood, however, that while the baffle members and spacing members are shown as secured together by means of the bolts 25 and the nuts 40, other equivalent constructions may be used, for example, the entire assembly of baffle

and spacing members might be cast as a single member to provide a unitary assembly.

In using the discharge device 4, it is directed to a fire, the valves 6 and 7 being opened so that the extinguishing fluid is discharged through the transversely extending orifices 14 and the axially extending orifice 12. As stated above, a larger proportion of the fluid is discharged through the orifices 14, the discharge therefrom travelling outwardly along the inner wall of the redirecting member 15. The longitudinal discharge through the axial orifice 12 travels outwardly, a portion thereof passing through the aperture 22 of the first baffle member 20 and the remainder being turned back and over the issuing stream fluid to provide a heat exchange relationship therebetween, this portion of the fluid being expanded and directed outwardly along the inner side of the shield 15 along with the stream of fluid issuing from the transverse orifices 14.

The portion of the longitudinal discharge fluid passing through the aperture 22, in part, passes through the aperture 31, while the remainder thereof is deflected back by the wall of the baffle member 29 to pass between the spaced baffle members 20 and 29 to join the fluid flow from the transverse orifices 14. The portion of the longitudinal discharge fluid passing through the apertures 31 is directed radially between the baffle members 29 and 35 to join the already issuing streams adjacent the inner wall of the redirecting member 15.

As the issuing streams merge towards the end 35 of the shield 15 further expansion takes place between the inner wall of the redirecting member 15 and the outer wall of the baffle member 35. A stream being provided practically free of eddy currents and in which a large proportion of the issuing fire extinguishing fluid has been converted to snow. By reason of the heat exchange relationship between the various streams of fluids flowing from the orifices a very cold stream is had readily forming snow, particularly under the influence of the back pressure provided by the comparatively restricted passages between the various baffle members and between their flanged ends and the inner wall of the shield 15.

From the foregoing description it will be seen that a nozzle or discharge device for carbon dioxide or other fluid liquefied under pressure has been provided, in accordance with the invention, in which the expanding fluid is surrounded by further expanded fluid of extremely low temperature and under conditions of back pressure such as facilitate the forming of a large proportion of snow. A construction is provided which is simple and economical in manufacture, efficient in operation, and durable in use.

While the invention has been described and illustrated in reference to a specific embodiment thereof, it will be understood that other embodiments may be resorted to without departing from the invention, for example, while the baffle members 20, 29 and 35 have been described as, and illustrated as being of conical shape and with a flattened end, it is to be understood that any other suitable equivalent constructions may be utilized. Alternatively, curved sections may be provided in which a portion of the issuing fluid is directed back over itself while being expanded, the fluid being thereafter redirected so as to prevent the formation of eddy currents to provide a smooth, evenly distributed

flow. Therefore, the form of the invention as set out above should be considered as illustrative and not as limiting the scope of the following claims.

I claim:

1. In a discharge nozzle for fire extinguishing fluid liquefied under pressure of the class wherein a body member has an inlet and an outlet passage, redirecting means are positioned opposite the outlet passage and spaced therefrom so that the fluid may expand therebetween and shaped to reverse the expanded stream issuing from the outlet passage back over itself in a heat exchange relationship, and means are provided to direct the expanded stream into a desired direction, the improvement which comprises an apertured baffle member interposed between the redirecting means and the outlet, and means to support the baffle member in position.

2. In a discharge nozzle for fire extinguishing fluid liquefied under pressure of the class wherein a body member has an inlet and an outlet passage, redirecting means are positioned opposite the outlet passage and spaced therefrom so that the fluid may expand therebetween and shaped to reverse the expanded stream issuing from the outlet passage back over itself in a heat exchange relationship, and means are provided to direct the expanded stream into a desired direction, the improvement which comprises a cone-shaped apertured baffle member interposed between the redirecting means and the outlet, and means to support the baffle member in position.

3. In a discharge nozzle for fire extinguishing fluid liquefied under pressure of the class wherein a body member has an inlet and an outlet passage, redirecting means are positioned opposite the outlet passage and spaced therefrom so that the fluid may expand therebetween and shaped to reverse the expanded stream issuing from the outlet passage back over itself in a heat exchange relationship, and means are provided to direct the expanded stream into a desired direction, the improvement which comprises a plurality of spaced apertured baffle members interposed between the redirecting means and the outlet, and means to support the baffle members in spaced position.

4. In a discharge nozzle for fire extinguishing fluid liquefied under pressure of the class wherein a body member has an inlet and an outlet passage, redirecting means are positioned opposite the outlet passage and spaced therefrom so that the fluid may expand therebetween and shaped to reverse the expanded stream issuing from the outlet passage back over itself in a heat exchange relationship, and means are provided to direct the expanded stream into a desired direction, the improvement which comprises an apertured baffle member interposed between the redirecting means and the outlet, and an outlet member having a plurality of trans-

versely extending apertures on the side thereof.

5. A discharge nozzle for fire extinguishing fluid liquefied under pressure comprising a body member having an inlet passage and an outlet passage, a hollow cone-shaped redirecting member having its base positioned about the outlet, an extension member for the outlet passage, the extension member having a plurality of apertures around its side, an apertured baffle member interposed between the outlet extension member and the cone-shaped redirecting member, and means to support the baffle member in position.

6. A discharge nozzle for fire extinguishing fluid liquefied under pressure comprising a body member having an inlet passage and an outlet passage, a hollow cone-shaped redirecting member having its base positioned about the outlet, an extension member for the outlet passage, the extension member having a plurality of apertures around its side, an apertured cone-shaped baffle member interposed between the outlet extension member and the cone-shaped redirecting member, and means to support the apertured cone-shaped baffle member in position.

7. A discharge nozzle for fire extinguishing fluid liquefied under pressure comprising a body member having an inlet passage and an outlet passage, a hollow cone-shaped redirecting member having its base positioned about the outlet, an extension member for the outlet passage, and a plurality of apertured cone-shaped baffle members interposed between the outlet extension member and the cone-shaped redirecting member, the outlet extension member extending into the adjacent cone-shaped baffle member.

8. A discharge nozzle for fire extinguishing fluid liquefied under pressure comprising a body member having an inlet passage and an outlet passage, an outlet passage extension member threadedly engaged in the outlet and having a plurality of apertures about its wall, a generally cylindrically shaped directing tube about the outlet and having an apertured end wall to receive the outlet end of the housing and supported thereby, a generally cone-shaped member having its smaller end directed outwardly, a plurality of generally cone-shaped baffle members having apertured ends interposed between the cone-shaped member and the outlet extension member, the outlet extension member extending into the first baffle member, spacing means to separate the first baffle member from the end of the outlet extension and to separate the baffle members from each other and from the cone-shaped member, supporting means to hold the baffle members and the cone-shaped member in position within the directing tube, the directing tube extending outwardly to the end of the cone-shaped member.
